UNITED STATES PATENT OFFICE.

FELIX KOHN, OF VIENNA, AUSTRIA-HUNGARY.

ROCKING-CHAIR.

No. 804,958.

Specification of Letters Patent.

Patented Nov. 21, 1905.

Application filed December 28, 1904. Serial No. 238,638.

To all whom it may concern:

Be it known that I, FELIX KOHN, a subject of the Emperor of Austria-Hungary, and a resident of Vienna, Austria-Hungary, have 5 invented certain new and useful Improvements in Rocking-Chairs, of which the following is a specification.

My invention relates to chairs, commonly known as "rocking-chairs," and has for its 10 object to provide a chair of this description which can be easily manufactured and which will at the same time be strong and durable, as well as comfortable.

Reference is to be had to the accompanying 15 drawings, in which—

Figure 1 is a side view of a rocking-chair made according to my invention, and Fig. 2 is a front view of the same.

A represents the rockers of the chair, which 20 in the present case are made from one piece of material bent into an ellipse with the ends overlapping, as at A', said ends being fastened together in any suitable manner—as, for instance, by screws A². The back-frame 25 B, to which the back C is fastened in any convenient manner, may also be made in one piece of material, which is bent into a U shape. The said back-frame B is secured to the rockers A at two places—for instance, by screws, 30 as shown at B' and B². The elliptical form of the rockers A makes it possible when assembling the parts to adjust this back-frame B in a variety of positions, so that the inclination of the back-frame B and back C may 35 be more or less, as desired. The seat portion D fits between the rockers and into the

back-frame and is secured at D' by means of screws or other fastening devices to the rockers A and to the back-frame B in any convenient manner at D². By making the rockers A in the form of an ellipse a gentle and easy rocking motion of the chair is secured, and said rockers A also at the same time form side portions or arm-rests for said chair. The seat portion and back portion of said 40 chair are also capable of a large variety of adjustments to suit existing conditions or individual tastes. This range of adjustment is limited in existing chairs owing to their construction, which necessitates the arrangement of said parts in certain positions. My 45 invention also does away with a great number of parts, and thus makes the chair simple in construction and easy of manufacture.

Various modifications may be made without departing from the nature of my invention.

What I claim, and desire to secure by Letters Patent, is—

A chair composed of elliptical rockers, having overlapping ends and forming arm-rests, of the back-frame B, secured to said rockers and of the seat D, secured between and to the rockers and to the back substantially set forth.

In testimony whereof I have hereunto subscribed my name in the presence of two subscribing witnesses.

FELIX KOHN.
